METHOD OF CUTTING A SKIN GRAFT

John D. Reese, Philadelphia, Pa.

Application July 31, 1945, Serial No. 607,988

5 Claims. (Cl. 128—305)

1

This invention relates to skin grafting, more particularly to the cutting of skin grafts from donor areas, and has for an object to provide an improved method of cutting such grafts.

In using dermatomes of the so called "drum" type, comprising a body member having a convex outer surface adapted to be coated with an adhesive for temporary retention of a skin graft thereon, together with a skin-cutting blade mounted for rotation and reciprocation relative to the convex surface for separating the skin graft from the body of the patient while the adhesive convex surface is rolled or rocked on the latter, as fully disclosed in United States Letters Patent No. 2,288,709, granted July 7, 1942, to G. J. Hood and in applicant's prior Patent No. 2,366,054, granted December 26, 1944, it is standard practice to coat the convex skin-engaging surface of the dermatome with a suitable adhesive, for example, a rubber cement, and likewise to coat the donor area of the patient with the same type of adhesive.

Under this prior practice, when the convex surface of the dermatome is rolled or rocked on the donor area, the two coats of adhesive cohere to each other and become, in effect, a single layer of adhesive connecting the dermatome surface and the donor area skin. The rolling action of the dermatome on the patient's body pulls upwardly on the skin and lifts it away from the body, this lifting force tending to cause failure of the adhesion between the layer of adhesive and the skin, or between the layer of adhesive and the metallic surface of the dermatome.

Obviously, any such failure of the adhesive connection between the donor area skin and the dermatome results in the cutting of holes in the graft of areas corresponding to the areas over which the adhesive fails.

The frequent failure of the adhesive used by the profession in the cutting of skin grafts in the manner explained above appears to result from the fact that the adhesive is of such character that if it adheres suitably to the convex metallic surface of the dermatome, then it does not adhere suitably to the human skin, and conversely, if the adhesive is such that it adheres properly to the human skin, it lacks the ability to adhere properly to the metal surface of the dermatome.

Since the "drum" type of dermatome came on the market several years ago, the profession has sought an adhesive which would adhere well to both the metal of the dermatome and to the skin of the donor area, but to the best of applicant's knowledge, no satisfactory adhesive is available for this purpose.

According to the present invention, it is proposed that two adhesives, of different characteristics, be used instead of the two coats of the same adhesive previously relied upon. More specifically, the adhesive applied to the dermatome convex surface would be one selected for its high

2

cohesiveness of adhesion for the particular material of which the dermatome convex surface is made (usually brass) while the adhesive applied to the donor area skin would be one selected for its high cohesiveness of adhesion for human skin.

Regardless of the types of adhesives selected, the two different adhesives will cohere to each other, when the dermatome is rolled on the donor area, more securely than either adhesive will adhere to the particular surface to which it is applied. Thus, the use of the proposed combination of two different adhesives assures of the least possibility of failure of the connection between the dermatome and the donor area skin during cutting of the graft.

Furthermore, it is proposed that the selection of the two adhesives take into consideration the relative cohesiveness of adhesion of the first adhesive to the dermatome surface and of the second adhesive to the donor area skin, it being desirable that the first adhesive adhere more securely to the dermatome than the second adhesive adheres to the graft, so that when the cutting of the graft has been completed, and it is desired to pull the graft from the dermatome convex surface, the adhesion between the skin graft and the adjacent coating of the second adhesive will fail, permitting removal of the skin graft free of all adhesive matter.

Therefore, another object of the invention is to provide, for use in the cutting of skin grafts, a novel method of temporarily retaining the graft on the dermatome.

35 A further object of the invention is to provide a method of cutting a skin graft, which method will assure separation of the cut graft from the dermatome free of all adhesive material used in cutting the graft.

These and other objects are effected by the invention as will be apparent from the following description and claims, taken in accordance with the accompanying drawing, forming a part of this application, in which:

45 Fig. 1 is a front elevational view, partially in section, of a dermatome for use in performing the method of the present invention;

Fig. 2 is a vertical sectional view, taken along the line II—II of Fig. 1, looking in the direction indicated by the arrows, portions of the structure being broken away for the sake of clearness;

Fig. 3 is a vertical sectional view, taken along the line III—III of Fig. 1, looking in the direction indicated by the arrows; and

55 Fig. 4 is an enlarged, fragmentary view of a portion of the structure shown in Fig. 3.

Referring now to the drawing more in detail, the dermatome, indicated in its entirety by the reference character 10, comprises a drum or body portion 11 of semi-cylindrical form, having a pair of spaced side walls 12 and 13, joined along their curved edges by a concave-convex wall 14,

constituting a skin-engaging or graft-receiving face.

A shaft 16 is journaled in a bearing 17 extending between, and supported by, the side walls 12 and 13, the longitudinal axis of the shaft 16 coinciding with the axis of generation of the convex surface 18 of the wall 14.

A pair of posts 20 and 21 are supported in parallel spaced-apart relation on the terminal portions of the shaft 16, and carry at their free outer ends 22 and 23, respectively, a knife-holding bar 24, on which is supported a graft-cutting blade or knife 25. Inasmuch as the space between the posts 20 and 21 is materially greater than the width of the drum or body member 11, the rectangle formed by the shaft 16, the posts 20 and 21, and the knife-holding bar 24 and knife 25 may be reciprocated and rotated as a unit relative to the body member 11. During such movement, the cutting edge of the knife will always be parallel to the convex surface 18 and at a predetermined distance therefrom, due to the axis of the shaft 16 coinciding with the axis of generation of the convex surface 18.

It is believed unnecessary to describe in this application, further details of construction of the dermatome 10, as sufficient structure has already been explained to enable those skilled in the art to understand and appreciate the novel features of the present invention, now to be described. If a more detailed description of the dermatome 10 is desired, reference may be had to applicant's prior Patent No. 2,366,054, granted December 26, 1944.

In accordance with the present invention, the convex surface 18 of the dermatome 10 is coated with an adhesive A (Fig. 4), which adhesive has a high coefficient of adhesion for the particular material of which the concave-convex wall 14 is made. Usually this material is brass, and a rubber base cement, for example, running board cement, may be found satisfactory. Running board cement consists of vulcanized rubber dissolved in acids.

Similarly, a coating of adhesive B is applied to the patients' donor area skin S, this second adhesive B having a high coefficient of adhesion for human skin. A rubber base cement, for example, artists' cement, may be employed with satisfactory results. Artists' cement consists of raw rubber dissolved in napthas.

Preferably, two different adhesives A and B are selected which will result in the adhesive A adhering tighter to the dermatome surface 18 than the adhesive B adheres to the skin S, with the result that when it is sought to remove the cut graft G from the dermatome to which it is secured by the cohering coatings of adhesive A and B, and force is applied to the graft G to pull it away from the dermatome surface 18, the adhesion between the adhesive B and the graft G will fail first, thereby permitting removal of the graft G free of the coating of adhesive B previously applied thereto, the coating of adhesive B cohering to the coating of adhesive A, and the latter adhering to the dermatome.

It may be desirable to add coloring matter to the adhesives if they do not naturally possess a color clearly distinguishing them from the surface to which they are to be applied, in order that the user may be sure that the coatings of adhesives completely cover the desired areas of the dermatome convex surface 18 and of the donor area skin S.

While the invention has been illustrated in

but one form, it will be obvious to those skilled in the art that it is not so limited, but is susceptible of various modifications and changes, as well as other applications, without departing from the spirit thereof.

What is claimed is:

1. In a method of cutting a skin graft with a dermatome having a convex skin-engaging surface, the steps of coating the convex surface with a first adhesive, and coating a section of donor area skin with a second adhesive which will adhere tighter to the first adhesive than to the skin and will adhere to the skin less tightly than the first adhesive adheres to the dermatome convex surface.

2. In a method of cutting a skin graft with a dermatome having a convex skin-engaging surface, the steps of coating said dermatome convex surface with a first adhesive which adheres tightly thereto, and coating a section of donor area skin with a second adhesive which adheres less tightly to the skin than the first adhesive does to the dermatome and than the second adhesive does to the first adhesive.

3. In a method of cutting a skin graft with a dermatome having a convex skin-engaging metallic surface, the steps of coating said convex metallic surface with a metal-adhesive cement, and coating a section of donor area skin with a human skin-adhesive cement whose coefficient of adhesion for the donor area skin is less than the coefficient of adhesion of the metal-adhesive cement for the metallic convex surface of the dermatome.

4. In a method of cutting a skin graft with a dermatome having a metallic skin-engaging surface, the steps of coating said metallic surface with a metal-adhesive material, and coating a donor area of skin with a human skin-adhesive material which adheres to the donor area skin less firmly than it does to the metal-adhesive material, and less firmly than the latter adheres to the dermatome metallic surface.

5. In a method of cutting a skin graft with a dermatome having a convex skin-engaging surface, the steps of coating said convex surface with a first rubber cement having a high coefficient of adhesion for the material of which said surface is composed, and coating a donor area of skin with a second rubber cement having a lower coefficient of adhesion for human skin than the first rubber cement has for the material of which the dermatome convex surface is composed, whereby, when the two rubber cements have been caused to cohere together by rocking the coated convex surface on the coated donor area skin, and a graft simultaneously cut from said donor area and left adhering to the dermatome convex surface by the two cohering cements, pulling of the graft from the dermatome will be effected by failure of the adhesion between the graft and the second rubber cement, rather than by failure of the adhesion between the first rubber cement and the dermatome or by failure of the cohesion between the two cements.
